HAIR DYEING TRAY

Benedict A. Militana, West Palm Beach, Fla.

Application July 14, 1954, Serial No. 31,421

Term of patent 7 years

(Cl. D86—10)

To all whom it may concern:

Be it known that I, Benedict A. Militana, a citizen of the United States, residing at West Palm Beach, in the county of Palm Beach and State of Florida, have invented a new, original, and ornamental Design for a Hair Dyeing Tray, of which the following is a specification, reference being had to the accompanying drawing, forming a part hereof.

I claim:

The ornamental design for a hair dyeing tray, substantially as shown.

No references cited.
